UNITED STATES PATENT OFFICE.

BENJAMIN J. BUCKINGHAM, OF CHICAGO, ILLINOIS, ASSIGNOR, BY MESNE ASSIGNMENTS, TO BUCKINGHAM-RAE COMPANY, OF CHICAGO, ILLINOIS, A CORPORATION OF ILLINOIS.

DISPLAY-RACK.

1,026,241.

Specification of Letters Patent.

Patented May 14, 1912.

Application filed September 26, 1906. Serial No. 336,228.

To all whom it may concern:

Be it known that I, BENJAMIN J. BUCKINGHAM, a citizen of the United States, residing at Chicago, in the county of Cook and State of Illinois, have invented a certain new and useful Improvement in Display-Racks, of which the following is a specification.

My invention relates to display racks and 10 has for its object to provide a simple and convenient holder or rack by means of which articles may be held for display or in storage.

The device is particularly adapted for 15 holding skirts and other articles of clothing where it is desirable to hold a considerable extent of smoothly folded material grasped between members which will at once take a firm grip upon the material 20 without danger of injury of any kind by removal or insertion.

The invention is illustrated in the accompanying drawings, wherein—

Figure 1 is an elevation of one form of 25 my device; Fig. 2, a plan view with parts broken away; Fig. 3, a section on line 3—3 of Fig. 2; Fig. 4, a detail in plan of a modification, and Fig. 5, a like view illustrating another modification.

Like letters of reference indicate like 30 parts in all the drawings.

I have shown and shall describe my display rack as consisting of a standard with a circular device rotatably connected therewith and carrying at its perimeter a number of co-acting holding elements or fingers. It will be obvious, however, that the particular form or shape of the device is not essential, nor the manner of its mounting, although I consider that the circular form 40 above shown and the rotatable mounting is preferable.

A represents a base preferably mounted on the casters A¹ A¹ and carrying a standard B which may conveniently be made of a piece of pipe or tubing in the end of which may be inserted the pointed block B¹ forming a pivot for the wheel like rack device. The latter, in my preferred construction, 50 consists of an upper disk of wood C, and a lower metal disk d, the latter having the central hub D¹ to extend over the standard B and the circular shoulder D² near its outer circumference, forming an off-set rim or flange part D³. The articles are designed

to be held between a number of elastic holding devices or fingers suitably connected with the disks C, D. These fingers consist of flat springs of considerable width in accordance with the size and weight of the 60 articles for which the rack is designed and they are preferably bent over or arched with their ends suitably secured to the disks. These fingers or holders I have indicated by the letters E.

In order to reinforce the fingers and to prevent them from being overbalanced or forced too much to one side or the other, I intersperse at suitable intervals rigid fingers or members which serve, in a sense, as stops 70 to limit the spring action of the fingers contained between them. In Figs. 1 to 3 inclusive I have shown these elements as consisting of the wooden fingers F. Preferably they extend some distance beyond the 75 ends of the spring fingers so as to prevent injury to the fingers if the rack should chance to be pushed over. The line x—x indicates the proper length of the wooden fingers to protect the spring fingers. It will 80 be seen, therefore, that the holding elements of the device are divided into groups, each group being in a certain sense independent in its action of the other groups. The fingers E and F may be secured to the disks 85 C, D in any desired manner. I have shown the fingers as provided with a perforation for a wire G and properly separated by spacing blocks or wedges H, the latter being secured to the upper or wooden disks by 90 the nails H¹. These wedges or blocks lie between the two ends of each of the springs. The fingers E, F preferably abut against the shoulder D², the disks C, D being held together by bolts H² H².

In Fig. 4 I have shown a modified form of reinforcement. In this construction the spring fingers lie adjacent to each other all the way around the device, the reinforcement consisting of rigid strips of wood or metal preferably employed in pairs and inserted between the spacing blocks H and the inside surfaces of the spring fingers. These reinforcements are indicated by the letter J. Any suitable number of fingers 100 may be thus reinforced, this construction likewise dividing the holding devices or fingers into groups.

In Fig. 5 I have shown a form of rack where the fingers are entirely dispensed 110

with. This form of construction will be suitable under certain circumstances, where, for example, very heavy springs are used or where the articles displayed are such as not to cause the overbalance of the spring fingers which the device of Figs. 2 and 4 are designed to obviate.

I wish it to be understood that I do not desire to be limited to the exact details of construction shown and described for obvious modifications will occur to any person skilled in the art. The circular form I consider preferable but the holder might, of course, be elliptical or have any other desired shape.

The use and operation of my invention are as follows: The articles to be suspended or exhibited are properly folded and then inserted between two adjacent spring fingers or between one such spring finger and the adjacent rigid stop. The presence of such a stop at intervals prevents the series of fingers being overbalanced or forced too much to one side when but a few fingers are in use and when they are all massed on one portion of the device. The action of any two spring fingers is to grasp the articles between each other at two points, one near the point of engagement with the central hub and the other near the point of termination of the finger arches. Between these points the fabric of the article to be supported is loosely held. By arranging these flat faced, outwardly arched and closed spring fingers in groups I can dispense with intermediate devices for as the fingers present flat surfaces in opposition to each other, there is no tendency to displacement, and as they are formed each with a closed arch at its outer end, the material is securely grasped without any reinforcing devices. In other words, the spring fingers, shaped as I have shown, reinforce each other. As previously suggested, these spring fingers may be arranged about a hub or ellipse, or on opposite sides of a bar, and the whole may be supported in any desired manner. With such a structure there is no waste space and no waste parts. The rigid stops are not always necessary.

Short arched spring-fingers are adapted to hold an object at a single clamping area. If the fingers are made of a certain properly proportioned length and strength, they will develop two clamping areas near their respective ends, with an intermediate area of low tension clamping capacity. The inner clamping area is due primarily to the elasticity of the metal of the springs, they being forced aside by the introduction of the article to be clamped. The outer clamping areas are due to the support given to the outer end of the spring-finger or its arch by something which is applied to the side thereof. If such fingers, as I have shown,

be not supported near the base of their outer arches, an object forced between two of them will simply push them aside until the outer clamping area practically coincides with the inner, and there is in effect but one clamping area. If the outer arches be supported on both sides at approximately their bases, the clamping areas will remain at substantially the same distance from each other under ordinary conditions, and if the spring-fingers are of sufficient length, there will be maintained between each pair two separated high tension clamping areas with an intermediate low tension section, and the device becomes suitable for supporting articles which require to be supported along a line of considerable length in order that they may hang properly. If such fingers are arranged in groups, and each is supported either by contact with another or by contact of the outer fingers of the group with rigid supports, such proper relation of the two clamping areas will result. The division by a series of rigid fingers or stops of sufficient length forms a series of discontinuous groups, each of which is, to all intents and purposes, separated from the other groups and forms a separate holder. The arrangement of the fingers in a circle so that each may be supported on each side by a spring finger forms a continuous group, and then no rigid stop for the purpose of supporting the arches of the fingers is necessary. The rigid fingers or stops, it will therefore be seen, perform the double function (1) of dividing the otherwise continuous group of spring-fingers into a series of discontinuous or small groups each of which is independent of the others, and is protected against lateral displacement, and (2) supporting the outer spring fingers at the bases of their arches, and thus holding or causing the several fingers in like manner to support each other, so that the relation of the two points or areas of high-tension clamping is maintained throughout such entire discontinuous group. The shorter inner supports or stops J J perform to a degree, the function first attributed to the rigid stops or fingers F, for they serve to divide the set of fingers into discontinuous, separately acting groups; but they are not long enough to perform the other function of the fingers F, because they do not support the spring-fingers with which they are associated at the bases of their respective arches.

The preferred form of my device is that shown in Fig. 5, when mounted as shown in Fig. 1, for I prefer to have a continuous or circularly arranged group of rotatably mounted spring-fingers. In such a structure, the use of intermediate rigid stops of either kind I find to be usually unnecessary. They appear to be entirely unnecessary in the use to which I have found my invention as particularly applicable, that is, the sup-

port of ladies' skirts, which require a relatively long line of support, and are best supported where there are two separated high tension clamping areas at the ends of 5 the line of support, with intermediate, relatively low-tension clamping areas.

I claim:

1. A garment holder comprising a support and a group of flat, outwardly arched spring-fingers in contact with each other along their 10 sides, and each supported on each side near the base of its arch, and all of such length and strength that they form near their respective ends high-tension clamping areas 15 with intermediate low-tension clamping surfaces.

2. A garment holder comprising a support and a group of flat, outwardly arched spring-fingers in contact with each other along their 20 sides, and each supported on each side near the base of its arch, and all of such length and strength that they form near their re-

spective ends high-tension clamping areas with intermediate low-tension clamping surfaces, the fingers arranged in a continuous 25 group, each supported on each side by the adjacent spring-fingers.

3. A garment holder comprising a support and a group of flat, outwardly arched spring-fingers in contact with each other along their 30 sides, and each supported on each side near the base of its arch by another spring-finger so as to form a continuous group, and all of such length and strength that they form near their respective ends high-tension clamping 35 areas with intermediate low-tension clamping surfaces, said support comprising a vertical part with a laterally projecting rotating part mounted thereon.

BENJAMIN J. BUCKINGHAM.
